UNITED STATES PATENT OFFICE

1,994,453

TYING MACHINE

Benjamin H. Bunn, Chicago, Ill., assignor to B. H.
Bunn Company, Chicago, Ill., a corporation of
Illinois

Application December 16, 1933, Serial No. 702,673

10 Claims. (Cl. 100—31)

In my Patent No. 1,606,290 of November 9, 1926, I have quite fully disclosed a tying machine for wrapping twine around a bundle and tying and severing the string. I have now invented a tying machine which is in many respects an improvement on the tying machine of my patent. My new tying machine may employ much of the structure and operation of that of my patent. Therefore, in disclosing my present invention I shall refer extensively to my prior patent for details of the mechanism and its operation.

One feature of my invention is that the bundle to be wrapped can be turned manually through ninety degrees where one wrap is to be longitudinal and the other transverse. To facilitate this turning operation I arrange the machine so that it makes one wrap and then stops while the operator turns the bundle in the other direction, when the machine can then make the other wrap. My present machine is peculiarly advantageous for wrapping bundles of non-rectangular contours such as are so often encountered in stacks of odd shaped labels which have to be wrapped. The longitudinal and transverse wraps need not be at right angles.

Preferably my present machine is arranged to make an initial single wrap longitudinally of the bundle and then, after the bundle is turned through ninety degrees, (or whatever odd angle may be required) to make a double—that is, two consecutive single—transverse wraps, with a single knot for the three wraps. Where the bundle has considerable length in proportion to its width, as in the case of the standard sized long envelope, the advantage of making the longitudinal wrap first is that an accurate centering of the longitudinal wrap is more necessary because of the greater likelihood of the longitudinal wrap working off the end corners. Where the bundle is manually positioned, setting the bundle for the longitudinal wrap first insures a more accurate position than the centering after the bundle is turned. If the longitudinal wrap be first, then the transverse wraps tend to hold the longitudinal wrap against moving transversely. There is not so much danger of the transverse wraps sliding off the package because the transverse wrap, even though not accurately centered longitudinally of the bundle, is still a long way from either end. There is not much chance of the transverse wraps shifting far enough to pass over an end corner and come loose. If the bundle is to have the security of a triple wrap, it is more economical of twine to have the two wraps transverse and the single wrap longitudinal.

My present machine is easily modified to produce other arrangements of wraps—one wrap each way with a single knot or two wraps each way with a single knot.

The foregoing, together with further objects, features and advantages of my invention, are set forth in the following description of specific embodiments thereof, and illustrated in the accompanying drawings, wherein:

Fig. 1 is a front elevational view of the machine 10 in its normal position, and is similar to Fig. 1 of my patent;

Fig. 2 is a vertical sectional view taken on the line 2—2 of Fig. 1, looking toward the wrapper arm end of the machine, with the parts also in 15 their normal positions, and is similar to Fig. 2 of my patent;

Fig. 3 is a plan view of the machine with the parts also in their normal position, and is similar to Fig. 5 of my patent, a portion of the guard 20 for the wrapping arm drive being broken away along the line 3—3 of Fig. 1;

Fig. 4 is a vertical sectional view taken on the line 4—4 of Fig. 1, looking in a direction opposite from Fig. 2, showing the parts also in their normal position, and is similar to Fig. 21 of my patent;

Fig. 5 is a fragmentary vertical sectional view taken on the line 5—5 of Fig. 3, looking toward the knotter and clutch control mechanism, but 30 showing the machine out of its normal position and in the position assumed in the operation at the time the knotter operating sector has just come into engagement with its cooperating knotter operating pinion, and is similar to Fig. 8 of 35 my patent;

Fig. 6 is a fragmentary vertical sectional view taken on the line 6—6 of Fig. 2, showing the parts in their normal position, and is similar to Fig. 4 of my patent, except that the view is looking in 40 the opposite direction from that in the latter;

Fig. 7 is a fragmentary elevation similar to the uppermost part of Fig. 2 but showing a modified arrangement of drive sprockets for the wrapping arm to produce a double wrap—one longitudinal 45 wrap and one transverse wrap;

Fig. 8 is an elevation of the cam disc of Fig. 5 on a reduced scale and showing the modified arcuate position of one of the cam blocks thereof as required for use with the modified sprockets 50 of Fig. 7; and

Figs. 9 and 10 are similar to Figs. 7 and 8 respectively, except that they show modifications giving a quadruple wrap—two transverse wraps and two longitudinal wraps.

I shall refer the reader to my prior patent for a more complete illustration and description of the structure and function of those parts of my present machine which are the same as those in the machine there disclosed. For the reader's convenience in referring from this specification back to my patent, I shall use the same reference characters in this application as used in my prior patent where they refer to the same or essentially the same parts, and for reference characters indicating new parts of my present machine not found in my prior patent I shall prefix the reference characters with the letter N. Reference characters thus prefixed with "N" will not necessarily have any analogy to the reference characters of my patent. I shall summarily describe so much of my present machine as is common to that of the patent.

The machine is built upon a suitable frame 50. The operating motor 52, which may be controlled by a conveniently located switch, and which may be kept running continuously, carries a motor pinion 54 which drives a gear 55 which normally idles on a shaft 56. A clutch 57, when engaged, will cause the gear 55 to drive its shaft 56, which in turn carries a pinion 61, driving a gear 62 fixed on shaft 63.

The clutch 57 is engaged and released by an arm 60, and this in turn is thrown into operation by depressing the treadle 110, which works through the vertical treadle rod 111, bellcrank 112 (Fig. 5) and the arm or link 115 against the tension of the retractile spring 114. Once the treadle has caused the clutch to engage, the shaft 63 will rotate in the direction of the arrow (Fig. 5), which, it will be remembered, shows the parts out of their normal position. A cam block mounting disc 107 is carried on the shaft 63.

In my prior patent, once the clutch had been engaged by operating the treadle, the motor would drive the shaft 63 and the disc 107 completely around until the cam block 108 engaged the roller on the end of the arm 115, which threw out the clutch. In my present machine I add an additional cam block N108. This results in throwing out the clutch after the shaft 63 has rotated only some ninety degrees.

What happens during that initial ninety degrees rotation of the shaft 63 I shall now describe.

Referring to Figs. 1, 4 and 6, the gear 62 is of double face, the face toward the right (Fig. 1) having teeth about the entire circumference, while the face to the left has a mutilated sector whose mutilation is arcuately substantially co-extensive with the smooth surfaced arcuate ledge projection indicated herein as 62' (Fig. 4).

The right face of the gear 62 is engaged by pinion 61. The left or mutilated face is aligned with a pinion 85, and the unmutilated teeth of the latter face engage the pinion 85. The pinion 85 in my prior patent drove the wrapper arm shaft, but in my present machine it is only an intermediate drive gear. It carries the rollers 105 which engage the arcuate ledge 62' to hold the pinion 85 against rotation while the latter comes at the mutilated sector of the gear 62. The journaling shaft on which the pinion 85 is fixed also carries a sprocket N10 drivingly connected by a chain N11 with a second sprocket N12 which, as shown in Fig. 6, is fixed on the wrapper arm shaft 86. During the previously mentioned initial rotation through some ninety degrees of the shaft 63, the unmutilated sector of the gear 62 drives the pinion 85 through two-thirds rotation. As the sprocket wheels N10 and N12 have a ratio

of three to two, this gives the wrapping arm a complete revolution, at the end of which the clutch is released until the operator again depresses the treadle.

I shall next describe what this initial rotation of the wrapping arm accomplishes on the bundle. First I shall describe the support upon which the bundle rests. I might explain that in my present machine the bundle supporting or work surfaces are entirely free of obstructions, permitting a ready shifting and turning of the bundle as desired. I dispense with the compressor 82 and the ejector 202 of my patent along with the operating mechanism therefor, including the vertical reciprocating rod 73, the actuating arm 67 therefor, the rock shaft 66, the arm 65 and the cam channel 64 in the gear 62 in my prior patent. However, certain phases of my invention are not inconsistent with the retention of the compressor and ejector.

The main or stationary table 84 is clear of all obstructions, leaving the bundle B, placed thereon, free to be shifted or rotated wherever desired. The island portion 98 of the top surface is of more extended area than in my patent and is pivotally mounted (Fig. 6) upon the wrapper arm 86, although in a slightly different manner. The island top 98 carries a vertical back plate N13, which functions somewhat as the stop disc 104 of my patent. It carries a trunnion N14 which is nonslidably journaled in an extension of the hub 89 of the wrapper arm 92. Thus, while the island top is supported on the rotating hub and shaft of the wrapper arm, it does not rotate with them. The stops 102 and 103 (Fig. 6) on the frame are engageable by a stop arm 101 depending from the island table 98 to keep the latter from rotating in either direction more than a few degrees.

The twine is led from a spool 94 through a friction guide 96 and through the hollow center of the tubular shaft 86 of the wrapping arm out the opposite end of the shaft and radially outwardly through an eye in the elbow of the wrapping arm to an eye 93 at the free end of the wrapping arm. From the eye 93 the string extends directly to the twine catcher 123 (see Fig. 1).

The bundle B, I have here illustrated as a stack of standard size long envelopes, with the length of the envelopes running parallel with the slot or gap between the stationary top 85 and the island top 98, the envelopes being more or less centered as regards the vertical plane passing through the axis of the wrapper arm shaft 86. The bundle is centered transversely on the said gap or slot. The initial rotation of the wrapping arm during the initial rotation of the shaft 63 through some ninety degrees, as previously explained, carries the twine completely around the bundle to form the first or longitudinal wrap of the "triple" wrap. The length of string necessary to encircle the bundle is, of course, pulled out from the spool 94 against the friction of the friction guide 96.

Referring to Fig. 3, since the crossed end of the first wrap comes on the reader's side of the initial reach of twine anchored to twine catcher 123, in order to engage the two reaches of twine to start the transverse wrap, it is necessary that the bundle be turned clockwise (Fig. 3). This the operator does manually, rotating the bundle through ninety degrees clockwise and aligning the left lateral edge of the bundle (Fig. 3) with the left lateral edge of the island 98, which brings

the lower lateral corner of the bundle adjacent the knotter beak, at which place the knot will be formed. The bundle is now ready for the transverse wrap or wraps. In the preferred embodiment here shown the longitudinal wrap is a single wrap and the transverse double.

To start the machine in operation again, to make two transverse wraps and tie the twine, the operator again depresses the treadle 110 to release the clutch control arm 90, which has been held out of engagement by the cam block N108. It will be seen from Fig. 105 that once the clutch release lever 60 has been returned to engaging position by release from the action of the cam block N108, the cam disc 107 together with the shaft 63 can rotate some two hundred and seventy degrees before the cam block 108 again throws the clutch out of engagement. During the first part of that two hundred and seventy degrees of movement, the two transverse wraps of twine are made, and during the remainder the knot is formed.

While the machine has been stopped by the disengagement of the clutch by the cam block N108 following the first wrap, during which time the operator turns the package into position for the transverse wrap, the wrapping arm has been held in its normal arcuate position by the engagement of the then stationary gear 62 with the pinion 85, and is not held stationary by the rollers 105 on the pinion 85, because the rollers are then out of engagement with the cooperating projection 62' on the gear 62.

As the shaft 63 again rotates, the wrapping arm is driven around two more times, making the double transverse wrap on the bundle. On each wrap the twine slips between the stop 102 and the stop arm 101 on the island top 98. By the time the second wrap is completed the rollers 105 on the wrapping arm drive pinion 85 and the projection 62' and the gear 62 have come into engagement and the pinion 85 has come to the mutilated face of the gear 62, with the result that the rollers 105 then hold the wrapping arm in its normal arcuate position during the remainder of the cycle of the machine, that is, during the knotting. As in my former patent, just before the final wrap is completed, the end 136 of the U-shaped member 135 (Figs. 3 and 5) is withdrawn to permit the twine to be caught by the twine catcher 123 along with the original end of the twine, this being accomplished by the cam 126b engaging the roller 130 on the bellcrank 127, which shifts the plate 132 carrying the member 135.

By the time the second transverse wrap is completed, the cam disc 107 has been rotated to the arcuate position where the roller 150 on the depending arm of the knotter carrier 148 enters the cam slot 152 of the cam disc 107 and tilts the carrier 148 about its pivot, throwing the knotter beak 159, 160 forwardly (Fig. 5) to engage the then side by side reaches of twine which are to be tied together. The gear sector 173 on the shaft 63 then engages the pinion 172, which, through the bevel gears 168 and 169 rotates the knotter beak 159, 160. The knotter mechanism, during the rotation of the knotter beak, progresses through the sequence best shown in Figs. 12 to 17 of my prior patent. At the proper time after the parallel reaches of string have been twisted about the knotter beak, the cam 156 causes the jaws of the beak to open and bite the two reaches of string, which are then withdrawn by the beak because of the carrier 148 being rocked back-

wardly again by the cam slot 153 in the cam disc 107. This withdrawal of the beak pulls out the characteristic loop of the knot. The stripping of the knot and the severing of the string is then done by the knotter mechanism, the reader being referred to my prior patent for a more detailed disclosure of the entire knotter mechanism and operation. The severing of the twine leaves the reach of twine extending from the end of the wrapper arm 92 still anchored on the twine catcher 123. After the knot has been formed and completed the shaft 63 has rotated the cam disc 107 to the position where the roller 116 on the end of the clutch throw-out arm 60 has reached the cam block N108, which throws out the clutch, permitting the gear 55 to idle on the shaft 56 so long as the motor continues to run.

The cycle of operation of the machine then being completed and the knotted string having been severed, the tied bundle is ready for the operator to remove.

When an unusually small bundle is to be wrapped and it is positioned considerably off center when being wrapped, there is a danger that the wrapping arm and bundle will cause an excessive amount of twine to be withdrawn. To remedy this I provide a draw back arm N16 which is pivotally mounted upon the wrapper arm near its hub. The twine is run through an eye in the outer end of the draw back arm N16. The arm N16 is normally urged out at an angle to the wrapper arm by a tension spring N17 between the arm N16 and a bracket N18 rigidly mounted on the hub of the wrapper arm but rotating therewith. The initial pull on the twine in wrapping a package first pulls this draw back arm down into parallelism with the radial reach of the wrapping arm 92 and then, if required, additional twine is withdrawn through the tension guide 96. The draw back arm N16 will automatically take up slack within certain limits.

I call particular attention to the feature of my present machine that it is not necessary that the bundle be rotated through ninety degrees as the angle between the longitudinal and transverse wraps. In the instance of stacks of odd shapes, such as, for example, diamond shaped labels, the wraps may be made at acute and complementary angles. Also, three parallel wraps, either horizontal or transverse, may be formed with a single knot by depressing the pedal after the first wrap, without turning the bundle.

For the reasons explained in the introduction to this specification, I generally prefer to make the initial single wrap the longitudinal wrap and the double wrap the transverse wrap, but the machine will operate equally well to make the first or single wrap a transverse wrap and the double wraps the longitudinal ones.

My present machine is also peculiarly well adapted for tying assorted sizes and shapes and characters of bundles in succession, there being no adjustment of the machine or any guides necessary.

In Figs. 7 and 8 I have shown the modifications in the ratio of the sprockets and the arcuate position of the cam block N108 which will give a double wrap—one wrap on the first depression of the treadle and one wrap on the second depression of the treadle. The sprockets N10a and N12a have a ratio of 1:1. This requires more arcuate movement of the shaft 63 to complete the first wrap. This is provided by a greater angle between the cam blocks N108 and 108 (compare Figs. 5 and 8).

- For a quadruple wrap—a double wrap (two successive wraps) on the first depression of the treadle and a double wrap on the second depression of the treadle—I use the modifications of Figs. 9 and 10. Here the sprockets N10a and N12a have the ratio of 2:1 (compare with the ratio 3:2 of the sprockets N10 and N12 of Fig. 2); and the cam block N108 is in a slightly different angular position with reference to the cam disc 107.
- 10 The simplicity of the changes in the machine to convert it from a triple wrap to a double wrap or to a quadruple wrap is a feature of my invention.
- I claim:
- 15 1. A power operated twine tying machine comprising a wrapper, a knotter, a control lever, a stop for stopping the wrapper after it has made one or more wraps but before operation of the knotter, and mechanism controlled by the lever for initiating operation of the wrapper for the first said wrap or wraps and for re-initiating operation of the wrapper, followed by operation of the knotter after said stopping.
- 20 2. The combination with a twine tying machine comprising wrapping and knotting mechanism which mechanism first forms a plurality of wraps with a string and then knots the string,—of a stop for stopping the operation of the wrapper after one or more complete wraps has been made but before the final wrap or wraps have been made and before the knotter has knotted the string, and a manually controlled lever for setting the mechanism into operation to complete the wraps and knot the string.
- 25 3. The combination with a twine tying machine comprising wrapping and knotting mechanism which mechanism first forms a plurality of wraps with a string and then knots the string,—of a stop for stopping the operation of the wrapper after one or more complete wraps has been made but before the final wraps or wraps have been made and before the knotter has knotted the string, and a manually controlled lever initiating operation of the wrapper and also setting the wrapper into continued operation to complete the wraps and knot the string after said stopping.
- 40 4. A power operated tying machine comprising a wrapper for forming two or more wraps of string about a bundle, a knotter for knotting the string, stop mechanism for stopping the wrapper after one or more wraps but before the final wrap, mechanism automatically initiating the operation of the knotter after the final wrap, and manually controlled lever means for initiating the operation of the wrapper and for starting the continued operation of the wrapper after termination by the stop mechanism.
- 45 5. A twine tying machine comprising a wrapping arm, a knotter, a continuously driven power shaft, a cam shaft having a pair of cams thereon, the cam shaft, during a cycle of the machine, driving the wrapping arm and the knotter, a clutch for engaging the power shaft with the cam shaft, clutch release mechanism operated by said cams, and a manually operable lever for engaging the clutch, the initial actuation of the lever engaging the clutch to drive the wrapping arm to form one or more wraps, at the completion of which one of the cams releases the clutch, and a second actuation of the lever engaging the clutch to form another one or more wraps followed by actuation of the knotter, at the completion of which the other cam releases the clutch to complete a cycle,
- 50 whereby the machine will form two series of wraps with a single knot.
- 55 6. A twine tying machine comprising a wrapping arm, an actuating shaft therefor, a pair of cams rotating in timed relation to the actuating shaft, a power shaft, a clutch between the power shaft and actuating shaft, release mechanism for the clutch actuated by the cams, and a manually operable lever for engaging the clutch, the initial actuation of the lever in the cycle of the machine engaging the clutch to drive the wrapping arm through one or more wraps followed by a release of the clutch by one of said cams, and the second actuation of the lever in a cycle of the machine re-engaging the clutch to drive the wrapper arm to make another one or more wraps followed by a release of the clutch by the other cam within the cycle of the machine.
- 60 7. The combination, with a tying machine having a wrapper and a knotter acting in sequence to wrap a bundle with a single twine in two successive series of one or more wraps each and to form a knot in the twine of the two series, of drive means for the wrapper, means for automatically discontinuing the operation of the wrapper for an unpredetermined time at the completion of each series of wraps, and a manual lever initiating operation of the wrapper after such discontinuance of operation at the completion of the first series of wraps.
- 65 8. The combination, with a tying machine having a wrapper and a knotter acting in sequence to wrap a bundle with a single twine in two successive series of one or more wraps each and to form a knot in the twine of the two series, of drive means for the wrapper, a manual lever for initiating the operation of the wrapper by the drive means, means for automatically discontinuing the operation of the wrapper for an unpredetermined time at the completion of each series of wraps, and means for supporting a bundle in wrapping position for manual rotation through an unpredetermined arc in the interim between the two series of wraps.
- 70 9. A tying machine comprising, in combination, a wrapping arm for successively wrapping a length of twine, in two series of one or more wraps each, about a bundle, a power shaft, a rotary drive member for the wrapping arm, a clutch between the shaft and drive member, a pair of cams on the drive member, a clutch release lever engageable by each cam to disengage the clutch, and a manually controlled lever for engaging the clutch, the respective cams acting to release the clutch after the first series and second series, respectively, of wraps is completed.
- 75 10. A tying machine comprising, in combination, a wrapping arm for successively wrapping a length of twine, in two series of one or more wraps each, about a bundle, a power shaft, a rotary drive member for the wrapping arm, a clutch between the shaft and drive member, a pair of cams on the drive member, a clutch release lever engageable by each cam to disengage the clutch, a manually controlled lever for engaging the clutch, the respective cams acting to release the clutch after the first series and second series, respectively, of wraps is completed, a knotter, and means for actuating the knotter, only after the second series of wraps is completed, to knot together the ends of the length of twine.
